Letter Patent No. 3307-Dated May 5-1866

Design for a Box.

I desire referred to in these Letter Patent and nothing part of the same shall when it may concern:

Be it known that Edward A. Marsh, of Chicopee, in the County of Hampden and State of Massachusetts, have invented and improved Design for a Box, and I do hereby declare that the following is a full, clear and exact description thereof, which will enable others skilled in the art to make and use the same, referring being had to the accompanying drawing, for a more particular specification.

The drawing is an enlarged back view of a box, fastened at one side by my design.

My invention consists in a design for a box which may be constructed in the usual manner with the usual materials of the United States of America

The portion of the pen that outlines the body of the shield is designated by the letter A, and through this at about the centre of a perforation with the outline of a star is made, the split in the pen turns out at the star. The chief of the shield which is of a different color from the rest of the pen is studded with stars, etc. This portion of the pen is in keeping with the American breast plate.

The remainder of the pen is constructed in a plain, simple style and upon the part which is sturdier the pen is divided into the two words "Shield Pen".

By this design I produce a pen which is simple and elegant.
